US00D974564S

(12) **United States Design Patent** (10) **Patent No.:** **US D974,564 S**
(45) **Date of Patent:** **** Jan. 3, 2023**

(54) **ANALYTE SENSOR DEVICE**

(71) Applicant: **ABBOTT DIABETES CARE INC.**,
Alameda, CA (US)

(72) Inventor: **Gary Ashley Stafford**, Hayward, CA
(US)

(73) Assignee: **ABBOTT DIABETES CARE INC.**,
Alameda, CA (US)

(**) Term: **15 Years**

(21) Appl. No.: **29/777,143**

(22) Filed: **Apr. 2, 2021**

Related U.S. Application Data

(63) Continuation of application No. 16/443,446, filed on Jun. 17, 2019, which is a continuation of application No. 15/786,272, filed on Oct. 17, 2017, now Pat. No. 10,362,972, which is a continuation of application No. 14/498,895, filed on Sep. 26, 2014, now Pat. No. 9,808,186, which is a continuation of application No. 13/717,501, filed on Dec. 17, 2012, now Pat. No. 8,862,198, which is a continuation of application No. 11/530,472, filed on Sep. 10, 2006, now Pat. No. 8,333,714.

CLAIM

The ornamental design for an analyte sensor device, as shown and described.

DESCRIPTION

FIG. 1 is a top perspective view of an analyte sensor device showing my new design;

FIG. 2 is a front elevation view thereof;

FIG. 3 is a top plan view thereof; and,

FIG. 4 is a bottom plan view thereof.

The dashed broken lines in the figures illustrate portions of the analyte sensor device that form no part of the claimed design.
